UNITED STATES PATENT OFFICE

2,418,366

DISHWASHING MACHINE

James H. Powers, Fort Wayne, Ind., assignor to
General Electric Company, a corporation of
New York

Application April 17, 1942, Serial No. 439,313

13 Claims. (Cl. 134—57)

1

The present invention relates to a dishwashing machine having a washing element which may be mounted in a sink drain opening and which may be operated by the motor of a waste disposal unit having a casing depending from the sink drain and in which a mixture of food waste and water is reduced to a flowable condition and discharged to a sewer system. The mounting of the dishwashing element in the sink drain opening eliminates the need for a separate tub, and the association of the dishwashing element with the waste disposal unit prevents clogging of the sewer drain system by food particles removed from the dishes during washing. These advantages can, if desired, be eliminated and the 15 constructional features may be applied to other washing machines.

The object of my invention is to provide an improved construction and arrangement in washing machines and in particular in a dishwashing machine of the above described type, and for a consideration of what I believe to be novel and my invention, attention is directed to the following description and the claims appended thereto.

In the accompanying drawings, Fig. 1 is a perspective view, partly broken away, of a dishwashing machine embodying my invention arranged in a sink equipped with a waste disposal unit; Fig. 2 is an exploded view of the sink drain opening and the sink stopper used to control the waste disposal unit; Fig. 3 is a top plan view, partly broken away, of the dishwashing machine; Fig. 4 is a sectional elevation of the dishwashing machine; Fig. 5 is a top plan view of the sink drain opening with the dishwashing element mounted therein; Fig. 6 is a sectional view taken on line 6—6 of Fig. 5; Fig. 7 is a sectional view taken on line 7—7 of Fig. 5; Fig. 8 is a sectional view taken on line 8—8 of Fig. 7; Fig. 9 is a sectional elevation through the sink drain opening and the sink stopper for controlling the waste disposal unit; Fig. 10 is an elevation of one of the flow interlocks for controlling the operation of the dishwasher and waste disposal unit; Fig. 11 is a sectional elevation of the flow interlock; Fig. 12 is a control diagram for the dishwasher and waste disposal unit; and Fig. 13 is a sectional view of the cover switch for the dishwasher.

Referring to the drawings, there is shown a sink 1 having a swivelled mixing faucet 2 connected through valves 3 and 4 to hot and cold water supply lines 5 and 6. In the bottom wall of the sink is a drain opening 7 defined by a

5 tapered wall 8 (Fig. 9) clamped between a flange 9 beneath the sink and a flange 10 at the upper end of a sleeve 11 depending through the drain opening. From one aspect the sleeve 11 defines a well at the bottom of the sink through which the sink drains. The flanges 9 and 10 are clamped by means of studs 12 in a flange 13 threaded on the lower end of the sleeve 11. The lower ends of the studs 12 project through holes 14 in a flange 15 at the upper end of a casing section 16 for a waste disposal unit shown in my application Serial No. 393,227, filed May 13, 1941, now Patent 2,322,058, patented June 15, 1943. The casing flange 15 is clamped to the under side of the flange 13 by nuts 17 threaded on the studs 12. The transmission of vibration from the casing 16 to the sink is prevented by a rubber ring 18 arranged between adjacent surfaces of the flanges 13 and 15 and having cylindrical portions 19 surrounding the studs 12. 20 Rubber washers 20 are arranged between the nuts 17 and the under side of the flange 15. At the lower end of the casing section 16 is fixed a casing section 21 within which is mounted a frusto-conical shredding chamber 22 described in detail in my above patent. At the lower end of the casing section 21 is fixed an electric motor 23 having a flywheel 24 on its shaft provided with impeller blades 25 for whirling a mixture 26 of food wastes and water around the shredding chamber 22 to reduce the same to a condition suitable for discharge through a trap 27 to a pipe 28 connected to a sewer system.

The operation of the waste disposal unit is 35 controlled by a sink stopper of the type disclosed in my Patent 2,185,037. The stopper comprises a disk 29 having a tapered surface 30 arranged to be pressed in sealing engagement with a tapered seat 31 at the lower end of the sleeve 11. Projecting inwardly from the lower end of the sleeve 11 are ledges 32 (Fig. 2) which cooperate with shoulders 33 of the disk 29 to locate the disk in the sink drain. Rotatably seated on the under side of the disk 29 is a disk 40 34 fixed to projection 35a on a handle 35. The ends of the handle overlap the top of the disk 29 and the projections 35a extend through ports 39 in the disk 29. The disks 29 and 34 are held together by spring-pressed pins 36 (Fig. 9) arranged in sockets 37 at the ends of the handle. At the lower end of the disk 34 are lugs 38 which cooperate with the under side of the ledges 32 upon twisting of the handle 35 to clamp the sink stopper in place. When the handle 35 is opposite the legend "Remove" on the flange 10,

the lugs 38 are out of engagement with the ledges 32 and the sink stopper can be removed. In this position ports 39 in the disk 29 are opposite or in register with suitable ports in the disk 34 (not shown) and the sink drain is accordingly open. When the handle 35 is turned to the position in which it is opposite the legend "Seal," the lugs 38 are moved beneath the ledges 32 and the sink stopper is locked in the sink drain opening. At the same time the ports in the disk 34 10 are moved out of register with the ports 39 in the disk 29 so that the sink drain opening is sealed. When the handle 35 is turned to a position opposite the legend "On" on the flange 10, the lugs 38 still engage the under side of the ledges 32 to hold the sink stopper in place and lugs 40 on the disk 34 engage the operating lever 41 of a switch 42 controlling the waste disposal unit 23 and move the switch from the "Off" position, illustrated in Figs. 9 and 12, to the "On" position. In this condition the waste disposal unit is conditioned for operation. Because the waste disposal unit cannot be operated until the sink stopper is locked in place, possible injury to the operator is prevented. Upon turning of the handle from the "On" position the switch operating lever 41 is returned to the "Off" position by a spring 43.

In the "On" position ports in the disks 29 and 34 are again in register so that water can drain into the waste disposal unit during its operation. This is necessary in order that the solid particles of the food wastes which are being reduced in size by the operation of the waste disposal unit may be mixed with water so as to provide a flowable mixture which will not clog the sewer drain pipes. The water supplied to the waste disposal unit should be cold so that greases in the food wastes will not be melted.

To insure the presence of the required minimum amount of cold water during the operation of the waste disposal unit, a flow interlock described in my Patent 2,244,402 is connected in the cold water supply line 6. The flow interlock comprises a casing 44 having inlet and outlet connections 45 and 46 for connection in the cold water supply line. The inlet connection 45 is in a nipple 45a threaded in to the casing 44. In the nipple 45a above the inlet connection 45 is a restricted orifice 47 at the lower end of an enlarged chamber 48 in which is slidably mounted a plunger 49. The plunger has spaced ribs 50 on its side walls which guide the movement of the plunger in the chamber. At the upper end of the plunger 49 is a stem 51 guided in an opening 52 in a spider 53 threaded on the upper end of the nipple 45a. Between the upper end of the nipple 45a and the spider 53 is a flange 54 on the plunger 49. In the lowermost position of the plunger, illustrated in Fig. 11, the flange 54 rests on the upper end of the nipple 45a and provides a more or less effective seal depending on the nature of the abutting surfaces. In the uppermost position of the plunger, the flange 54 engages the under side of the spider. The plunger is held in its lowermost position by an offset arm 55 on the inner end of a spindle 56 journaled in the side wall of the flow interlock casing 44. Fixed to the outer end of the spindle 56 is an arm 57 the lower end of which is urged in a clockwise direction, as viewed in Fig. 10, by a compression spring 57a having an adjusting screw 58. The upper end of the arm 57 is provided with an adjusting screw 59 for cooperation with the operating member 60 of a normally closed "micro switch" 61.

When there is no flow in the cold water line, the plunger 49 is held by the spring 57a in its lowermost position, as illustrated in Fig. 11, and the screw 59 engages the switch operating member 60 and holds the switch in the open position. Upon opening of the cold water faucet, as explained in detail in my above patent, the plunger 49 is raised to a position which is substantially wholly dependent upon the rate of flow in the cold water line. This position may be varied by adjustment of the set screws 58 and 59. When the proper flow of cold water is obtained, the arm 57 is moved in a counterclockwise direction, moving the screw 59 away from the switch operating member 60 and causing the switch to close. The switch 61 remains closed so long as the proper flow of cold water is maintained so that the operation of the waste disposal unit is in effect under the control of the cold water faucet.

In the control diagram (Fig. 12) the sink stopper operated switch 42 and the flow interlock switch 61 are shown connected in series with the waste disposal unit motor 23 through a circuit which includes line conductor 62, motor 23, conductor 63, flow interlock switch 61, conductor 64, sink stopper switch 42, and line conductor 65.

When the machine is to be used for washing dishes, the sink stopper is removed and a dishwashing element is mounted in the sink drain opening. The dishwashing element comprises a housing or carrier having a cylindrical portion 66 at its upper end arranged to telescope within the drain sleeve 11 and having a tapered seat 67 co-operating with the seat 31 to provide a fluid-tight seal. Below the seat 67 the housing is reduced in diameter to clear the inner edge of the seat 31, and the reduced portion is provided with indentations 68 to clear the ledges 32. The inner walls of the indentations 68 are continuations of a cylindrical section 69 at the lower end of the housing. Projecting from the housing within the indentations 68 are pins 70 which cooperate with the under side of the ledges 32 upon clockwise turning of the housing (Figs. 5 and 7) to lock the housing in the sink drain opening. A handle bail 71 is provided for convenience in inserting and turning the housing. The dishwasher housing does not touch the operating lever 41 for the sink stopper switch 42 so the control circuit for the waste disposal unit is open when the dishwasher housing is in place. The lower end of the housing is partially closed by an annular ring 72 integral with the cylindrical housing section 69. At the center of the ring 72 is a bearing housing 73 supported by three spaced radial ribs 74 extending between the bearing housing and the under side of the ring 72. The space between the bearing housing 73 and the central opening in the annular ring 72 provides a drain opening for the housing which is open at all times. This drain opening is large enough to permit the free passage of food particles removed from the dishes during washing. Journaled in the bearing housing 73 is a shaft 74a having a dishwashing impeller 75 fixed to its upper end and having its lower end connected by a bayonet joint 76 to the upper end of a tubular shaft 77. The lower end of the shaft 77 is connected through a spring 78 (Fig. 4) to a coupling member 79 having projections 80 arranged to fit in corresponding depressions 81 in the waste disposal unit flywheel 24. This type of coupling is one which can easily be moved into engagement, and, due to the spring 78, the dishwashing housing can be inserted in the sink drain even though the projections 80

do not line up with the depressions 81. The projections will move into the depressions as soon as the flywheel turns to the proper position.

The construction of the dishwasher impeller 75 is conventional. It comprises two helical blades 82 spiralled around a hub 83. The outer edge of the blades has a running clearance with the inside of the cylindrical housing section 69, with the upper surface of the annular ring 72, and also with a shroud ring 84 which forms an extension of the cylindrical housing section 69. The upper end of the shroud ring 84 projects slightly above the bottom of the sink and serves to direct the liquid from the impeller blades 82 upward into the sink. The liquid is conducted to the impeller from the bottom of the sink through an annular passage 85 between the shroud ring 84 and the housing section 66 and from this annular passage through passages 86 between the lower end of the shroud ring 84 and the housing section 68. From the passages 86 the water is conducted to the impeller through slots 87 in the shroud ring. The slots 87 are somewhat above the lower ends of the impeller blades 82 and accordingly the water falls directly onto the impeller blades and is immediately thrown upward through the shroud ring. The impeller blades centrifugally create a fluid pressure head which effectively prevents leakage of water through the drain opening between the bearing housing 73 and the opening at the center of the annular ring 72. To further aid in preventing any slight leakage at this drain opening, there are shown additional impeller blades 88 intermediate the impeller blades 82, but in actual practice it has been found that the blades 88 are not necessary. Apparently there is a whirling annulus of water at the lower end of the housing which at all times during the rotation of the impeller at its normal running speed has an internal diameter greater than the diameter of the housing drain opening. The housing drain opening accordingly is effectively sealed at all times during the rotation of the impeller. As soon as the rotation of the impeller is stopped, the water in the sink is of course free to drain. From one aspect the housing drain opening could be considered as centrifugally sealed. The centrifugal seal eliminates the need for a drain valve which might fail to seal due to food particles collecting on the seats.

The dishes to be washed are loaded in a rack 89 having suitable provisions for holding the dishes, as shown in Fig. 3, so that the dirty surfaces face toward the water spray discharged by the impeller blades. The impeller discharge is generally upward, as indicated by the arrows 90 in Fig. 4, and also spirally around the sink in a direction perpendicular to the arrows 90. The dishes are spiralled around the impeller in the same general direction as the spray. During dishwashing, the top of the sink is closed by a cover 91 resting on a ledge 92 at the top of the sink. Adjacent the sink back board 93 the ledge 92 is provided with a switch 94 (Fig. 13) having an operating member 95 actuated by a pin 96 on the under side of a flexible diaphragm 97 fixed across an opening 98 in the ledge. The switch operating member 95 is biased upwardly to the position shown in Fig. 13, and the pin 96 accordingly projects above the seat 92. When the cover is in place, the pin 96 is depressed and moves the switch operating member 95 to the closed position. With this arrangement the dishwashing machine cannot be operated until the cover is in

place. This keeps water from being sprayed outside the sink. The cover has an opening 99 which is positioned to register with the mixing faucet 2. The opening 99 may be closed by a swivelled plate 100.

In the use of the dishwasher the sink should be filled with a small quantity of hot water. The quantity of water is not very critical and may vary from one to two gallons in a sink of the size illustrated which is about 20" square and 10" deep. In the present machine the amount of hot water supplied is controlled by a flow interlock 101 in the hot water supply line of the construction shown in Figs. 10 and 11. The flow interlock 101 has a switch 102 connected in series with a solenoid 103 which actuates a switch 104 in series with the cover switch 94 and the motor 23. The flow interlock switch 102 is closed by the flow interlock plunger 51 by opening the hot water faucet 3 sufficiently to cause a predetermined flow of hot water. Since very hot water should be used in the dishwasher, the hot water faucet can be opened to allow a smaller flow until the water reaches the desired temperature and can then be opened wider to cause the closing of the flow interlock switch. Upon closure of the flow interlock switch a circuit is completed through the solenoid 103 which extends from line conductor 62 through the flow interlock switch 102, conductor 105, and solenoid 103 to line conductor 65. Upon energizing of the solenoid 103, the switch 104 is closed and is latched in the closed position by a latch 106. The closing of the switch 104 completes a circuit through the motor 23 which extends from line conductor 62 through motor 23, conductor 63, conductor 107, cover switch 94, conductor 108, and switch 104 to line conductor 65. The closing of the motor circuit starts the rotation of the impeller, and accordingly water, which thereafter flows into the sink through the cover opening 99, is kept in the sink by the centrifugal sealing action resulting from the rotation of the impeller 75. The closure of the motor switch 104 also completes a circuit through an indicating lamp 109, a thermostatic switch 110, and a heating element 111. This circuit extends from line conductor 62 through the flow interlock switch 102 to the indicating lamp 109, and from the indicating lamp 109 through the thermostatic switch 110, heating element 111, conductor 108, and motor switch 104 to line conductor 65. At the end of a predetermined time the heating element 111 causes the opening of the thermostatic switch 110 and indicates to the operator that the required amount of water has been placed in the sink. At this time the operator manually closes the hot water faucet 3 and may add detergent through the cover opening 99. When the dishes have been washed for the required length of time the motor is stopped by pushing a latch release knob 112 to cause the opening of the motor switch 104. This stops the rotation of the impeller 75 and at the same time stops the centrifugal sealing of the drain opening so that the water together with the food particles washed from the dishes drains into the waste disposal unit. The washing operation is followed by one or more rinsing operations which are carried out in the same manner as washing except that no detergent is added.

For each washing or rinsing operation the operator positions the mixing faucet above the cover opening 99, opens the hot water faucet 3 until the indicating lamp 109 lights, closes the hot water faucet when the indicating lamp 109

goes out, and pushes the latch release knob 112 when the operation is completed. The indicating lamp and latch release knob are mounted on the back board of the sink so as to be out of the way and yet conveniently accessible.

Due to the flow interlock controls in the hot and cold water supply lines, the waste disposal unit can be operated with cold water and the dishwashing unit can be operated only with hot water.

What I claim as new and desire to secure by Letters Patent of the United States is:

1. In a dishwasher, a sink having a drain opening, a waste disposal unit below the sink having a shredding chamber with an inlet connected to the sink drain opening and an outlet for connection with a sewer system, a rotary shredding element in said chamber, a rotatable impeller for washing dishes in the sink, a carrier for said impeller removably mountable in the sink drain opening and having journaled therein a drive shaft for the impeller connectable to said shredding element and having a drain to the shredding chamber when mounted in said opening, and provisions for selectively preventing the flow of water through said drain.

2. In a dishwasher, a sink having a drain opening, a housing removably seated in said opening, an impeller journaled on a vertical axis in said housing for discharging water upward into the sink, an intake passage for the impeller leading from the bottom of the sink through said housing onto the lower part of the impeller, a part for connection with a sewer system depending from said drain opening, a motor drive for the impeller having a coupling within said part for connection with the impeller, and a drain opening in said housing positioned beneath said impeller so that during rotation of the impeller leakage is prevented by centrifugal forces set up by the impeller.

3. In a dishwasher, a sink having a drain opening, a waste disposal unit below the sink having a shredding chamber with an inlet connected to the sink drain opening and an outlet for connection with a sewer system, a rotary shredding element in said chamber, a rotatable impeller for circulating water in the sink, a carrier for said impeller removably sealed in the sink drain opening and having a drive shaft for the impeller connectable to said shredding element, passages in the carrier for conducting water from the sink to the impeller, a drain opening in the carrier around the drive shaft below said passages, and blades on the impeller cooperating with said carrier drain opening to create a pressure head preventing leakage during rotation of the impeller.

4. In a dishwasher, a sink having a drain opening, a waste disposal unit below the sink having a shredding chamber with an inlet connected to the sink drain opening and an outlet for connection with a sewer system, a rotary shredding element in said chamber, a carrier removably insertable in said opening, a shaft journaled therein, a rotatable impeller on the shaft for circulating water in the sink, a shroud ring surrounding the impeller, passages around the shroud ring leading from the sink to the lower end of the impeller, a drain opening in the carrier below said passages, and a centrifugal element on said shaft for creating a pressure head preventing leakage through the carrier drain opening during rotation of the shaft, and means for connecting said shaft to said rotary shredding element.

5. In a combined dishwasher and waste disposal

unit, a sink having a drain, a waste disposal unit having a shredding chamber for connection with a sewer system depending from the drain, a shredding impeller in said chamber, a control interlocking with a cold water supply to limit the operation of the impeller to shred waste material

5 to such times as cold water is supplied to the shredding chamber, a dishwashing impeller removably seated in the drain opening and having 10 a coupling for connection with the shredding impeller, a control interlocking with a hot water supply to limit the operation of the dishwashing impeller to such times as hot water is supplied to the sink, and means for disabling the 15 first mentioned control during operation of the dishwashing impeller.

6. In a combined dishwasher and waste disposal unit, a waste disposal unit having a shredding chamber for connection with a sewer system, a shredding impeller in said chamber, a dishwashing compartment draining to said shredding chamber, a dishwashing element, a control for operation of the impeller responsive to the supply of cold water, a control for operation of the dishwashing element responsive to the supply of hot water, and provisions for disabling the first mentioned control during dishwashing.

7. In a washing machine, a tub, a drain in the bottom of the tub, an impeller for washing material in the tub having a centrifugal element arranged to create a fluid pressure preventing leakage through said drain during operation of the impeller, a control for the washing machine including a device responsive to the flow of water 30 to the tub for starting the operation of the impeller at the start of the filling of the tub, timing means for indicating the length of time water is supplied to the tub, and means for stopping the impeller to drain the tub.

8. In a dishwasher, a sink having a drain opening, a waste disposal unit below the sink having a shredding chamber with an inlet connected to the sink drain opening and an outlet for connection with a sewer system, a rotary shredding element in said chamber, a rotatable impeller for washing dishes in the sink, a carrier for said impeller removably sealed in said drain opening, a drain opening in the carrier, an impeller drive shaft in the carrier extending through the carrier drain opening and connectable to said shredding element, and means on the drive shaft for centrifugally creating a fluid pressure preventing leakage through the carrier drain opening during rotation of the shaft.

9. In a dishwasher, a sink having a drain opening, a part for connection with a sewer system depending from said opening, a housing removably sealed in said opening, a drain passage in said housing to said part, an impeller above said drain passage journaled in said housing for circulating water in the sink, a centrifugal element above and overlapping said drain passage for creating a suction preventing leakage through said drain passage during rotation of said element, and a power drive for rotating said impeller and centrifugal element having a coupling in said part.

10. In a dishwasher, a sink having a drain opening, a waste disposal unit below the sink having a shredding chamber with an inlet connected to the sink drain opening and an outlet for connection with a sewer system, a rotary shredding element in said chamber, a rotatable impeller for washing dishes in the sink, a carrier surrounding the impeller and removably

sealed in the sink drain opening, a drive shaft for the impeller journaled in the carrier and connectable to said shredding element, a drain through the carrier to the shredding chamber, and a centrifugal element rotated by the shaft for creating a suction at said opening preventing the flow of water through the carrier into the shredding chamber during rotation of the shaft.

11. In a dishwasher, a tub, an impeller at the bottom of the tub rotatable on a vertical axis for forcing water upward into the tub, a shroud ring surrounding the impeller and cooperating therewith to direct water upwardly, a drain opening inward of the periphery of and below the impeller, and walls in the tub in proximity to said shroud ring which define passages for conducting water to the impeller at a region where the impeller imparts sufficient upward force to the water to prevent leakage through the drain opening during rotation of the impeller.

12. In a dishwasher, a tub, an impeller at the bottom of the tub rotatable on a vertical axis for forcing water upward into the tub, a shroud ring in the tub surrounding the impeller for confining the water during rotation of the impeller to an annulus surrounding the impeller, a drain opening radially inward of the inner periphery of the lower part of said annulus, and a wall which surrounds the shroud ring and defines therewith a passage for conducting water from the bottom of the tub to the lower outer part of said annulus.

13. In a dishwasher, a sink having a drain opening, a waste disposal unit below the sink having a shredding chamber with an inlet connected to the sink drain opening and an outlet

for connection with a sewer system, a rotary shredding element in said chamber, a carrier removably insertable in said opening, a shaft journaled therein, means for connecting said shaft to said rotary shredding element, a rotatable impeller on the shaft for circulating water in the sink, a shroud ring surrounding the impeller, passages around the shroud ring leading from the sink to the lower end of the impeller, and a drain opening in the carrier below said passages.
